UNITED STATES PATENT OFFICE.

BERNARD H. WUEBBEN, OF DAYTON, OHIO, ASSIGNOR TO THE RECORDING AND COMPUTING MACHINES COMPANY, OF DAYTON, OHIO, A CORPORATION OF OHIO.

FARE-BOX.

1,252,527.

Specification of Letters Patent.

Patented Jan. 8, 1918.

Application filed December 30, 1916. Serial No. 139,919.

To all whom it may concern:

Be it known that I, BERNARD H. WUEBBEN, a citizen of the United States, residing at Dayton, in the county of Montgomery and State of Ohio, have invented certain new and useful Improvements in Fare-Boxes, of which the following is a specification, reference being had therein to the accompanying drawing.

10 This invention relates to fare boxes.

An object of the invention is to provide a construction which will separate the coins and tickets as they are deposited within the box. In particular the object of the invention is to provide a construction and arrangement of parts which will separate the coins from the tickets, directing the coins to a position to be registered or to a proper receptacle for holding the same, and directing the tickets to be canceled and deposited.

It is a further object of the invention to prevent the tickets from escaping through the coin openings and to sift all the coins from the separator before a canceling operation on the tickets, or a similar disposal of them, takes place. The construction is also such that if a ticket should escape with the coins it would be greatly mutilated and could not be used again.

30 It is also an object of the invention to provide a construction which will allow the coins to escape easily while preventing the escape of the tickets therewith, the latter being retained in a position to be canceled, 35 the canceling operation taking place after the coins have been separated so that the coins will not interfere with the canceling operation or injure the canceling mechanism.

40 A further object of the invention is to provide a construction in which the separator is located above the coin receptacle from which the fares are lifted to a position to be registered and to provide common operating means for separating the coins from the tickets and for the lifting device.

Another object of the invention is to provide means for retaining the fare in view for inspection, which means is to be operated by the mechanism operating the parts of the separator so that the fares will fall within the separator only when the parts thereof are in proper position to receive them.

Another object of the invention is to pre-

vent a fare or group of fares from leaving the inspection plates until the preceding fare or group of fares has been sifted and the tickets canceled, thus preventing congestion of the mechanism, providing time for proper inspection, and complete disposal in an orderly manner of each batch of fares.

In the accompanying drawings, Figure 1 is a side elevation of a section of one embodiment of the invention, with parts omitted for the sake of clearness; Fig. 2 is a rear elevation of a section thereof with parts omitted; Fig. 3 is a front elevation of the separator; Fig. 4 is a plan view thereof; Fig. 5 is a rear elevation thereof; Fig. 6 is a sectional elevation of the separator showing the position of the parts during the canceling operation and looking toward the front; Fig. 7 is a similar sectional view showing the position of the parts as the tickets and coins fall into the same; Fig. 8 is a sectional view showing the inspection plates closed; and Figs. 9 and 10 are detail views illustrating the construction of cams used for actuating the several parts.

The embodiment of the invention herein shown is applied to a machine of the character shown and described in Letters Patent No. 1,190,936, granted July 11, 1916, although the invention is applicable to machines of other types.

Referring to Fig. 1 the box comprises the usual casing or support 1 on which is mounted an inclined rotatable disk 2 adapted to lift coins from the hopper 3 into position to be registered, as was fully described in the patent above mentioned. As shown in Figs. 1 and 2 the rear of the disk is provided with a crown gear 4. Adjacent the gear 4 is a vertical shaft 5 provided with a pinion 6 meshing with the crown gear, and a bevel gear 7 at one end below the pinion 6 which is driven by means of a corresponding bevel 8 upon the shaft 9 which is provided with a suitable actuating handle 10. Mounted upon the upper portion of the shaft 5 is a rotatable cylinder 11 provided with racks of different lengths with which the slide gear 12 is adapted to engage according to the distance which it is moved by the differential mechanism 13 controlled by the coins upon the lifting disk, the construction being similar to that disclosed in the patent above mentioned. The rotation

of the cylinder by means of the handle 10 rotates this gear 12 which is suitably connected with the counters 14 to actuate the same. The coins after being registered are 5 discharged through the chute 15 (Figs. 1 and 2) into a suitable drawer 16. Mounted above the hopper 3 of the coin lifting mechanism is a separator provided with a suitable casing 17. The separator is open at 10 the bottom and communicates with the hopper 3, as indicated at 18, whereby the coins as they are separated will fall into the hopper and are then ready to be lifted into registering position. The upper portion of the 15 separator is provided with a suitable chute or hopper 19 into which the tickets and coins are deposited by the passengers. Rotatably mounted within the separator is a drum 20 provided with radial spokes 20'. This drum 20 is provided with two series of openings 21 which are of sufficient size to allow coins to drop through should they fall upon the drum. Extending around the drum are three grooves 22. The drum is also provided 25 with transversely extending teeth or serrations 23 and prongs 24 arranged substantially as shown and adapted to engage the tickets for lifting the same. This drum is adapted to rotate in the direction of the 30 row and is driven from the handle 10. For this purpose a transversely extending shaft 25 is journaled immediately above the vertical shaft 5 and is provided with a bevel gear 26 meshing with a gear 26' on the end 35 of the vertical shaft. The shaft 25 is provided at one end with a bevel gear 27 meshing with a bevel gear 28 on a shaft 29 extending forwardly. A gear 30 is suitably journaled upon a pin 31 mounted upon the 40 rear of the casing 17, as is clearly shown in Figs. 1 and 5. This gear has an interlocking engagement with the forward end 32 of the shaft 29. Movement is transmitted from the gear 30 to the idle gear 32' and 45 from the idle gear 32' to a gear 33 fixed to the shaft upon which the drum is fixed.

In order to separate the coins and tickets I have provided a sifting plate or sieve 34 having a shaft 35 journaled within the casing 17 immediately below and to one side of the drum. The sifting plate is curved and when in a raised position is adapted to closely engage the drum, the curvature of the drum being substantially the same as the 50 curvature of the adjacent portion of the sifting plate. From an inspection of the drawings it will be seen that the plate is adapted to occupy lower positions, as shown in Figs. 2, 7 and 8, and to closely engage the drum, as shown in Figs. 3 and 6. Mounted upon the fixed part of the casing is a suitable stop 36 which co-operates with the corresponding stop 37 upon the sifting plate to limit the downward movement 55 thereof. This plate is provided with holes

38 of such size as to allow the coins to freely drop therethrough and yet arranged to prevent the passage of the tickets therethrough. For preventing these tickets from passing through the holes and escaping with the 70 coins and to insure that the drum will pick up the same and carry them around to canceling position, immediately below each hole there is provided a downwardly extending semiannular flange 39, substantially as 75 shown. This flange is arranged on the farther side of the hole in the direction in which the drum is rotating. Furthermore, the inner surface of this flange is inclined, substantially as indicated at 40. By referring to Figs. 3, 6, 7 and 8 the exact arrangement and inclination of this portion of the sifting device with relation to the direction of the rotation of the wheel may be noticed. Mounted below each of the holes within the 80 sifting plate is a semiannular guard 41 arranged to prevent the tickets from falling through the openings but to allow the coins to freely escape. The sifting plate is also provided with flat portions between the respective holes above mentioned and for purpose of preventing any coin from lying upon these flat portions I have provided holes 42 therein through which the pins 43 are adapted to project during the downward movement of the sifting plate to dislodge any surplus coins. Pins 43 are mounted upon a curved member 44 attached at one end 45 to the casing and at its opposite end 46 to a guard plate or deflector 47. The arrangement 90 above described has been found to be very efficient in allowing the coins to escape but preventing the escape of the tickets therewith and it is also efficient in retaining the tickets in position to be caught up by the 95 drum for canceling the same.

Mounted immediately below the hopper 19 there has been provided a pair of inspection plates 43' and 44' fixed to shafts 45' and 46' which are journaled in the upper portion of 100 the casing 17. The shaft 35 upon which the sifting plate is mounted, as is clearly shown in Fig. 3, is provided with an arm 47' located at the front of the casing. In a like manner the shaft 45' is provided with an 110 arm 48 centrally fixed thereto and a spring 49 connects one end of this arm and the arm 47'. The spring is arranged so that it performs the dual function of normally tending to keep the inspection plates closed and the sifting plate in raised position. The shaft 46' is also provided with an arm 50 and to this arm is pivoted a link 51 and to the unattached end of the cross arm 48 is a second link 52. The links 51 and 52 are pivoted together at their lower ends, as indicated at 53 and these ends are in turn pivoted to an arm 54 provided with an upwardly projecting lug 54'. The arm 54 is pivoted at its end opposite the attachment 125

of the links thereto to a portion of the shaft 35. It will be seen that by the connection above described the spring 49 controls both plates through the connecting links 52 and 51.

In order to prevent the movement of the inspection plates above a horizontal plane I have provided, as is shown in Figs. 2 and 5, an arm 50' fixed to the shaft 45' adapted to 10 engage the stop 51'. In order to actuate the inspection plates and to raise and lower the sifting plate the shaft 55 upon which the drum is mounted is provided with a suitable gear 56 at one end which meshes with an 15 idle gear 57, the latter gear meshing in turn with the gear 58 suitably journaled on the front of the separator. The gear 58 has fixed to it an inner cam 59 and an outer cam 60 of peculiar construction, as shown par- 20 ticularly in Figs. 9 and 10. The cam 59 is adapted to engage periodically the lug 54' upon the pivoted arm 54 while the cam 60 is adapted to engage the pivoted arm 47' to 25 actuate the same. It is thought that the pec- ular construction of the cam 60 will be ap- 30 parent from a description of the operation of this part of the mechanism.

Assuming that the parts of the separator are in the position shown in Fig. 6, as the 35 drum rotates the portion 61 of the cam 60 will engage the pivoted arm 47' and lower the sifting plate to its lowest position. Immediately after the sifting plate is lowered and while it is retained in this position by 40 means of its cam the cam 59 engages the lug 54' on the pivoted arm 54 and opens the inspection plates and allows the coins and tickets to fall therefrom. The inspection plates are then immediately closed and after 45 the closure of the inspection plates the portion 62 of the cam 60 allows the sifting plate to move upwardly a portion of its distance quickly and with a distinct jar. It should be noticed that the portion 62 prevents the 50 sifting plate from moving to its uppermost position against the drum. After being raised to this position, however, the cam portion 63 immediately lowers the sifting plate again and the cam portion 64 allows 55 the same to slowly rise so that any coins remaining thereon will either slide off or be jarred off. As the drum continues to rotate the straight portion 65 of the cam 60 allows the sifting plate to move up quickly into en- 60 gagement with the drum. The drum thus rotates drawing the tickets up into position to be canceled and the operation is repeated. It will, therefore, be seen that the movement of the sifting plate back and forth tends to 65 cause the coins to be jarred through the openings thereof into the hopper of the coin lifting portion of the mechanism. The general arrangement of sifting plate is such as to prevent the escape of tickets through the openings and to insure the proper support

therefor so that the drum in its final operation will draw the tickets up into canceling position.

Located at the top of the separator I have provided suitable inking and marking mechanism for canceling the tickets as they are drawn up by the drum. For this purpose the upper portion of the casing is provided with downwardly extending slots 67. The marker or roller 68 having a shaft 69 is rotatably mounted at the lower ends of the slots in engagement with the drum. This marker is provided with transversely ex- 70 tendsing serrations and with grooves 75 which allow the free passage of the prongs 24. Mounted upon a shaft 71 also located in the slots 67 is a suitable inking roller 72. Means have been provided for retaining the marker and inking roller within their slots and for this purpose each side of the casing 80 is provided with a detent 73 having a portion 74 hooked over the end of the shaft of the inking roller. These detents are held in engagement with the shaft by means of springs 75. The tickets after being marked 85 by their passage between the marker 69 and roller 20 are directed into a suitable chute leading to a receptacle for receiving the tickets. As is clearly illustrated in Figs. 1 to 3, 5 to 8, the chute comprises an upper 90 guard or directing plate 76 and a lower plate 77 which acts as a stripping device to strip the tickets off of the drum. The plates 76 and 77 and the sides of the casing 95 constitutes the chute which is connected with a receptacle 77' indicated in Fig. 2. The stripping device 77 is provided with projections 78 riding within the grooves of the drum 20, whereby better stripping action is insured. Recesses 79 are also provided upon the strip- 100 105 110 115 120 125 130

The operation of the mechanism so far described is substantially as follows. The 115 tickets and coins being deposited upon the inspection plates, as indicated in Fig. 6, the handle 10 is rotated which causes the sifting plate to assume its lowered position. While the sifting plate is in its lowered 120 position the inspection plates are opened through the instrumentality of the mechanism described upon a continued rotation of the handle. These inspection plates are then closed and the sifting plate is raised to an intermediate point with a jar in order to dislodge any coins mounted thereon. It is immediately returned to lowered position and again raised gradually at first so that coins which are still mounted thereon will 130

tend to slide off without causing the tickets to escape through the openings. Meanwhile any coins that happen to drop upon the drum will escape through the holes therein, the drum serving no purpose up to this point except to operate the several mechanisms of the inspection plates and sifting device. The sifting device then approaches quite closely the periphery of the drum and the 10 prongs thereon will engage any tickets which are located upon the sifting device within the holes or supported by the curved semi-annular members below the holes. The tickets thus engaged will be raised and concealed by a passage through the drum and marker 68, after which they are stripped from the drum and are deposited in a suitable receptacle. Should, by chance, any of the tickets become lodged within the 15 openings or escape, the same will be jammed by reason of the rotation of the drum and will be mutilated to such an extent that they cannot be again used. Continued rotation of the handle 10 will then cause the coins to be 20 lifted into engagement with the differential mechanism above mentioned and to be registered upon the counters 14, the single handle 10 serving to cause the operations of all the parts of the mechanism above described. 25

30 In order to provide a conductor controlled device for checking up the number of tickets which will be found in the several drawers or receptacles therefor and the coins registered upon the counters 14 I have provided a suitable conductor-controlled counter and means for actuating the same. This counter and accompanying actuating mechanism is shown in Figs. 1 and 2. A suitable support 35 is provided therefor at the upper end of 40 the fare box in alignment with the counters 14 and adjacent thereto. Upon this support are mounted the counters 86 which are provided with suitable transmission gears mounted upon the shaft 87 for transmitting 45 the movement from the units wheel to the tenths wheel, etc. Fixed to the units counter of the series of counters 86 is a gear 88 which is held in position by means of a 50 spring-controlled detent 89 mounted upon the shaft 87. The gear 88 meshes with a suitable gear 90 fixed to a shaft 91 suitably journaled in the support. Fixed to the gear 90 is also a suitable ratchet 91'. Rotatably mounted upon the shaft 91 is a sector operating handle 92 which is held in raised position by means of a spring 93 attached, as indicated at 94, to the sector operating handle above the pivot thereof and also having one end attached to the shaft 87, whereby 55 the handle is always held in or tends to assume a position at the extreme left, as shown in Fig. 1. Pivoted to the sector handle is a suitable pawl 95 which is held in engagement with the ratchet 91' by means of a 60 spring 96 connecting the same with the sec-

tor handle. It will be seen that as the handle is pulled to the right in Fig. 1 the pawl will engage the ratchet, locking the gear 90 therewith and rotating the gear 88, which gear transmits motion to the counters. The 70 arrangement of the parts is such that a single movement of the operating handle to the right is sufficient to advance the counters, say three points, before it is necessary to release the same to allow the pawl to engage 75 the teeth of the ratchet at a point farther up or at a point farther to the left, as shown in Fig. 1. I have also provided a suitable audible signal to be used in connection with this counter mechanism so that the advance of 80 the counter one unit will ring the bell. For this purpose I have pivoted a hammer 97 at a point 98 adjacent the gear 88. The hammer is held in one position by means of a spring 99 and is provided with a projection 100 lying in the path of the teeth upon the gear 88. It will be noticed that as the gear advances one point the same will engage the projection 100 swinging the hammer 97 on its pivot, the spring returning the same to 90 normal position. As the hammer swings upon its pivot it engages and rings the bell 101 mounted upon a suitable bracket 102. It will therefore be seen that as a ticket or coin is deposited within the fare box the 95 conductor must pull the sector handle of the last described counting mechanism and that the pawl remains in engagement with one of the teeth of the ratchet and causes the rotation of the gearing. The handle normally tends to move to the left, as shown in Fig. 1, so that the pawl can engage the teeth of the ratchet successively. At the same time that the mechanism is operated to advance the counter one point the teeth 105 upon the gear 88 will engage the hammer 97 and cause the same to ring the bell, making the registration apparent to any one present in the car or thereabout.

While I have shown and described one 110 embodiment of the invention it will be understood that the same has been chosen for the purposes of illustration and that I do not desire to be limited to the details of construction shown and described, for obvious 115 modifications will occur to a person skilled in the art.

Having thus fully described my invention, what I claim as new and desire to secure by Letters Patent, is:—

1. In a mechanism of the character described, a pivoted sifting device, pivoted inspection plates, means tending to keep said sifting device in raised position and said inspection plates closed, a cam for operating said inspection plates to open the same when the sifting device is in lowered position, and a cam for operating said sifting device.

2. In a mechanism of the character de-

scribed, a rotatable drum, a curved sifting device adapted to fit around said drum and pivoted therebelow, inspection plates, and means for successively operating said sifting device and said inspection plates, said means being controlled by the operation of the drum.

3. In a device of the character described, a sifting plate, a pair of inspection plates pivoted at their outer ends, arms fixed to the pivots of said plates, a link pivoted at one end to each of said arms, a pivoted lever to which the opposite ends of said links are connected, a spring connecting the inspection plates and the sifting plate for normally keeping the inspection plates in closed position and the sifting plate in raised position, and means for actuating said inspection plates and sifting plate.

20 4. In a mechanism of the character described, a rotatable drum, a curved sifting plate pivoted below said drum and adapted to be moved up into engagement therewith, a spring tending normally to so move said sifting plate into position against the drum, and a rotatable cam for lowering said sifting plate and allowing the same to rise to jar the coins and to move into engagement with the drum.

30 5. In a mechanism of the character described, a sifting plate provided with openings to allow the coins to fall therethrough, flat portions provided with holes, and pins adapted to engage said holes to dislodge coins from the flat portions of said plate.

6. In a mechanism of the character described, a pivoted sifting plate, and a cam provided with a portion to move the sifting plate in the one direction and to retain the same in that position while the coins and tickets fall thereon, a portion to allow a quick upward movement to jar the coins, a portion to return the sifting plate to the first-mentioned position, and a portion to allow the movement again in the opposite direction.

7. In a mechanism of the character described, a pivoted sifting plate, a cam provided with a portion to move the sifting plate in one direction and to retain the same in that position while the coins and tickets fall thereon, a portion to allow a quick upward movement to jar the coins, a portion to return the sifting plate to the first-mentioned position, a portion to allow movement in the opposite direction near to the drum, a portion to permit close engagement of the sifting plate and drum and a portion to allow the movement again in the direction opposite from the first-mentioned direction.

8. In a mechanism of the character described, a pivoted sifting plate with holes therein, a cam provided with a portion to move the sifting plate in one direction and to retain the same in that position while the coins and tickets fall thereon, a portion to allow a quick upward movement to jar the coins, a portion to return the sifting plate to the first-mentioned position, and a portion to allow the movement again in the opposite direction.

9. In a mechanism of the character described, a pivoted sifting plate with holes therein and bridges spanning said holes, a cam provided with a portion to move the sifting plate in one direction and to retain the same in that position while the coins and tickets fall thereon, a portion to allow a quick upward movement to jar the coins, a portion to return the sifting plate to the first-mentioned position, and a portion to allow the movement again in the opposite direction.

10. In a mechanism of the character described, a casing, a perforated drum rotatably mounted in said casing, devices on the periphery of said drum to catch up tickets, a marking device coöperating with said drum, a chute for stripping the tickets from the drum after being canceled, a curved sifting plate pivoted below and adjacent the periphery of said drum and provided with openings therein, a plurality of flanges arranged completely below the plate and partially surrounding the openings, guards extending below the openings for preventing the escape of tickets therethrough, means fixed to the casing for dislodging coins from flat portions of said plate, a pair of inspection plates at the upper end of the casing, a spring connecting said inspection plates and sifting plate for retaining the first in closed position and the second in raised position against the drum, a cam for actuating said inspection plates to open the same when the sifting plate is in lowered position, a cam provided with a portion to lower the sifting plate and to retain the same in such position while the inspection plates are open, a portion to allow a quick partial upward movement of the sifting plate to jar the coins, a portion to return the sifting plate to lowered position, and a portion to allow a gradual upward movement of the sifting plate to a position adjacent the drum, and means for rotating the drum and cams.

110 In testimony whereof, I affix my signature.

BERNARD H. WUEBBEN.
